PULSATILE FLUID PUMP SYSTEM

RELATED APPLICATIONS

The present application is one of four applications being filed on the same day and bearing publication numbers 2022/0265994 and 2022/0265993, and patent numbers 11,236,741 and 11,300,119. Each of these related applications and patents, other than the present application, is hereby incorporated herein by reference in its entirety.

TECHNICAL FIELD

The present invention relates to pulsatile fluid pumps, and more particularly to pulsatile fluid pumps suitable for pumping blood.

BACKGROUND ART

A pulsatile fluid pump is taught in U.S. Pat. No. 7,850,593 ("our prior patent") for an invention of Douglas Vincent and Matthew Murphy, who are co-inventors of the present invention. Our prior patent discloses a pump actuated by a linear motor configured to cause reciprocation of a flexible membrane, serving as a wall of a fluid housing, that is in turn coupled to a pair of ball valves, in a manner as to implement pulsatile fluid flow.

SUMMARY OF THE EMBODIMENTS

In accordance with one embodiment of the invention, a pulsatile fluid pump system includes a pump-valving assembly including a chamber and a set of ports; and a diaphragm assembly coupled to the chamber and including an edge-mounted flexible diaphragm having an inside surface for contacting a fluid in the chamber to be pumped and an outside surface exposed to ambient air. The diaphragm assembly and the pump-valving assembly are configured as an integral pump assembly. The pulsatile fluid pump system further includes a linear motor having a magnet and a coil, the magnet moving in relation to the coil, the coil having an electrical input. The pulsatile fluid pump system also includes a control housing rigidly coupled to the linear motor and a controller system having an electrical output coupled to the electrical input of the coil, the controller system defining an electrical waveform at the electrical output to cause desired operation of the diaphragm. The integral pump assembly is configured to be removably coupled to the control housing, and the diaphragm assembly of the integral pump assembly is configured to be removably coupled to the linear motor.

Alternatively or in addition, the pulsatile fluid pump system further includes a push rod, coupled to the linear motor, and configured for removable attachment to the diaphragm assembly. Also alternatively or in addition, the pulsatile fluid pump system further includes a force sensor coupled between the linear motor and the push rod.

In a related embodiment, the pulsatile fluid pump system further includes a flexible seal surrounding the push rod. Alternatively or in addition, the pulsatile fluid pump system further includes a set of cooling fins thermally coupled to the coil of the linear motor. Also alternatively or in addition, the push rod is slidably attached to the diaphragm assembly.

Alternatively or in addition, the controller system includes a microprocessor, and the controller system is

configured to execute a waveform program defining an electrical waveform at the electrical output to cause desired operation of the diaphragm.

In a further related embodiment, the integral pump assembly has a peripheral flange, and the control housing has a channel configured to removably receive the peripheral flange if the diaphragm assembly of the integral pump assembly is removably coupled to the linear motor. Alternatively or in addition, at least one of the peripheral flange and the channel has a set of compliant members to physically bias the peripheral flange in the control housing. Also alternatively or in addition, each compliant member includes a spring.

Further alternatively or in addition, the pulsatile fluid pump system further includes a latch configured to constrain the integral pump assembly in the channel. Alternatively or in addition, the set of compliant members is included in a set of ball detents.

In a related embodiment, the diaphragm assembly further includes a coupler configured to reciprocate with the diaphragm, and the integral pump assembly includes a pump housing having a neck configured to maintain axial and rotational alignment of the coupler.

In accordance with an alternative embodiment of the invention, an integral pump assembly for a pulsatile fluid pump system includes a pump-valving assembly including a chamber and a set of ports; and a diaphragm assembly coupled to the chamber and including an edge-mount flexible diaphragm having an inside surface for contacting a fluid in the chamber to be pumped and an outside surface exposed to ambient air. The pump-valving assembly and diaphragm assembly are disposed in an integral pump assembly housing configured to be removably coupled to a control housing for the pulsatile pump system, the control housing including a linear motor having a magnet and a coil, the magnet moving in relation to the coil, the coil having an electrical input, the control housing rigidly coupled to the linear motor. The electrical input of the coil is coupled to the electrical output of a controller system defining an electrical waveform at the electrical output to cause desired operation of the diaphragm. The diaphragm assembly of the integral pump assembly is similarly configured to be removably coupled to the linear motor.

Alternatively or in addition, the integral pump assembly housing includes a peripheral flange, and the control housing has a channel configured to removably receive the peripheral flange if the diaphragm assembly of the integral pump assembly is removably coupled to the linear motor. Also alternatively or in addition, the peripheral flange has a set of compliant members to physically bias the peripheral flange in the control housing.

In a related embodiment, each compliant member includes a spring. Alternatively or in addition, the set of compliant members is included in a set of ball detents.

In accordance with yet another embodiment of the invention, a control housing is provided for removably receiving and being removably coupled to an integral pump assembly for a pulsatile fluid pump system. The integral pump assembly includes (i) a pump-valving assembly including a chamber and a set of ports; and (ii) a diaphragm assembly coupled to the chamber and including an edge-mount flexible diaphragm having an inside surface for contacting a fluid in the chamber to be pumped and an outside surface exposed to ambient air. The pump-valving assembly and diaphragm assembly are disposed in an integral pump assembly housing. The control housing includes a chassis; a linear motor, rigidly coupled to the chassis, and having a magnet and a

coil, the magnet moving in relation to the coil, the coil having an electrical input; and a controller system having an electrical output coupled to the electrical input of the coil, the controller system defining an electrical waveform at the electrical output to cause desired operation of the diaphragm. The control housing is configured to be removably coupled to the integral pump assembly, and the linear motor is configured to be removably coupled to the diaphragm assembly of the integral pump assembly.

Alternatively or in addition, the integral pump assembly has a peripheral flange, and the control housing further has a channel configured to removably receive the peripheral flange if the diaphragm assembly of the integral pump assembly is removably coupled to the linear motor.

BRIEF DESCRIPTION OF THE DRAWINGS

The foregoing features of embodiments will be more readily understood by reference to the following detailed description, taken with reference to the accompanying drawings, in which:

FIG. 1 is a vertical section of the pulsatile fluid pump system 301 showing the controller system 311, power amplifier 321, linear motor 330 (coil 332, cooling fins 334, and magnet 339), push rod assembly 341, flexible seal 351, control housing 361, and the integral pump assembly 200.

FIG. 2 is an example of the touch-sensitive graphic display 400 user interface showing the user-specifiable motor parameters 401, flow characteristics 411, and user-specifiable input parameters 421.

FIG. 3 is a vertical section of the push rod assembly 341.

FIG. 4 is a vertical section of the linear motor 330.

FIG. 5 is a block diagram describing a waveform program 511.

FIG. 6 is a block diagram describing a first embodiment 511a of the waveform program 511.

FIG. 7 is a block diagram describing a second embodiment 511b of the waveform program 511.

FIG. 8 is a block diagram describing a graphics program 611.

FIG. 9 is a horizontal section of a pump-valving assembly 101 in accordance with an embodiment of the present invention, wherein the pump-valving assembly 101 is in diastole mode in which the chamber 102 is being filled.

FIG. 10 is a vertical section of an integral pump assembly 200 showing a diaphragm assembly 201 mounted to a pump-valving assembly 101 in diastole mode, in which the chamber 102 is being filled.

DETAILED DESCRIPTION OF SPECIFIC EMBODIMENTS

Definitions. As used in this description and the accompanying claims, the following terms shall have the meanings indicated, unless the context otherwise requires:

A "set" includes at least one member.

An "electrical waveform" is a waveform selected from the group consisting of an electrical current waveform, a voltage waveform, and combinations thereof.

The term "user-specifiable input parameter" includes a user-definable attribute pertinent to an alarm setting or calculation for a user interface, such as low flow limit 421a, high flow limit 421b, and body surface area 421c (BSA), as well as combinations of any of the foregoing attributes.

The term "user-specifiable parameter defining the performance of the linear motor" in the course of pumping includes a motor performance attribute such as stroke

strength 401a, beat rate 401b, flow rate, average flow rate, stroke volume, flow index, pulse pressure, output pressure, magnet displacement, as well as combinations of any of the foregoing attributes.

The term "physical flow characteristic" includes a measured attribute such as stroke strength, beat rate, flow rate, average flow rate 411a, stroke volume 411b, flow index 411c, flow rate waveform 412, stroke volume waveform 413, duration over which the pump has been running (e.g., measured by timer 414), as well as combinations of any of the foregoing attributes. If an attribute is user-specified in a given embodiment of the present invention, then measurement of the attribute is of subsidiary importance since its value has been specified. Similarly, if an attribute being measured has primary importance a given embodiment of the present invention, then the parameter would not have been user-specified.

"Normal flow" is flow from the entrance to the inlet port 111 through the chamber 102 to the exit of the outlet port 121.

A "slight reversal of flow" past a ball in a ball check valve is a small, controlled amount of desired reverse flow past the ball before the ball is seated in a closed position.

"Diastole mode" is a phase of operation of a pulsatile pump, according to embodiments of the present invention, during which the diaphragm 202 of the pump-valving assembly 200 is pulled away from the chamber 102 so as to create negative pressure within the chamber 102, inlet ball check valve assembly 110, and third tapered tract 126, but not the fourth tapered tract 122.

"Systole mode" is a phase of operation of a pulsatile pump, according to embodiments of the present invention, during which the diaphragm 202 of the pump-valving assembly 200 is pushed towards the chamber 102, so as to create positive pressure within the chamber 102, outlet ball check valve assembly 120, and the second tapered tract 116, but not the first tapered tract 112.

FIG. 1 is a vertical section of the pulsatile fluid pump system 301 showing the controller system 311 (with electrical output 311b), power amplifier 321 (with electrical input 321a and electrical output 321b), linear motor 330 (comprised of a stationary member 331 which includes a coil 332 [with electrical input 332a], a frame 333, and cooling fins 334, and a moving member which includes a spring 338 of FIG. 4 and a magnet 339), position sensor 371, push rod assembly 341 (comprised of a push rod 342 and force sensor 372), flexible seal 351, control housing 361, and chassis 363. An integral pump assembly 200 (comprised of the pump-valving assembly 101 with chamber 102, diaphragm assembly 201, and peripheral flange 221a) is configured to be removably coupled to the control housing 361, and the diaphragm assembly 201 of the integral pump assembly 200 is configured to be removably coupled to the linear motor 330. The integral pump assembly 200 has a flange 221a that slides in the channel 362. The integral pump assembly 200 is held in place by the peripheral flange 221a and compliant member 221c of FIG. 10 in the channel 362 within the control housing 361. (In these figures, like numbered items correspond to similar components across different figures.)

FIG. 2 is an example of a touch-sensitive graphic display 400 user interface showing user-specifiable motor parameters 401. In this interface appear parameters stroke strength 401a and beat rate 401b. These parameters are a subset of user-specifiable parameters defining the performance of the linear motor. Additionally, in this interface appear flow characteristics 411 (average flow rate 411a, stroke volume

411b, flow index **411c**), flow rate waveform **412**, stroke volume waveform **413**, and timer **414**. These flow-based attributes are a subset of physical flow characteristics. Additionally, the interface displays user-specifiable inputs **421** (low flow limit **421a**, high flow limit **421b**, and body surface area **421c**).

FIG. 3 is a vertical section of the push rod assembly **341** comprised of the push rod **342** and force sensor **372**. The push rod may have a neck with a first radial dimension, disposed on an upper portion of the push rod, and capped by a head having a second radial dimension larger than the first radial dimension.

FIG. 4 is a vertical section of the linear motor **330**, showing the coil **332** with electrical input **332a**, the frame **333**, the magnet centering spring **338**, and the magnet **339**. Other components and detail of the motor are provided in FIG. 1.

In FIG. 5, the waveform program **511** is a computer program executed by the controller system **311** microprocessor **311c** which accepts input from a set of sensors **370** (including position sensor **371** of FIG. 1, force sensor **372** of FIGS. 1 and 3, and an external flow sensor **373** of FIG. 8), a set of user-specifiable motor parameters **401** (stroke strength **401a** and beat rate **401b**) defining performance of a linear motor **330** in the course of pumping. Additionally, FIG. 5 shows a set of user-specifiable input parameters **421** (low flow limit **421a**, high flow limit **421b**, and body surface area **421c**). The waveform program **511** outputs an electrical waveform **512**, the result of a set of algorithms **513**, at the electrical output **311b**. The electrical output **311b** is coupled to electrical input **332a** of linear motor **330**.

There is growing consensus that desirable characteristics of a pulsatile pump should include both sufficient hemodynamic energy and a human-like waveform architecture. To evaluate pulsatile flow, we choose the human heart as the best model: it delivers a proper stroke volume at a natural cadence with a physiologic rest at the end of each stroke, adapting to the physiologic demands of the patient by adjusting the cardiac output, as the product of stroke volume and beat rate. Via the left ventricle, the human heart provides hemodynamic energy that results in a pressure wave that propagates fully through the elastic arterial tree. It appears that only a biomimetic stroke volume delivered in a biomimetic time frame (like the native systolic contraction produced by the heart) allows the elastic arterial tree to properly relax during the diastolic phase. Use of continuous flow devices stretches the elastic arterial wall but never allows proper relaxation, creating constant and atypical stress on the endothelial cells and interfering with natural baroreceptor sympathetic and parasympathetic signaling, thus disrupting the body's homeostatic control state.

The waveform program **511** causes the pulsatile fluid pump system **301** to replicate the ability of the left ventricle of the human heart to deliver physiological hemodynamic energy proportional to a user-specified stroke strength **401a** by causing delivery of the necessary fraction of the stroke volume of a pump chamber **102** in a physiologic natural cadence at a user-specified beat rate **401b**. It is a user (a perfusionist) of the pulsatile fluid pump system **301** who adjusts the stroke strength **401a** (an indirect specification of stroke volume) and beat rate **401b** to meet the physiologic demand of the patient. Furthermore, the waveform program **511** replicates the physiologic rest at the end of each stroke, thereby allowing natural relaxation of the arterial tree.

The structure of a pulsatile pump in accordance with various embodiments of the present invention can usefully reflect attributes of the human heart. The human heart is

preload sensitive—the heart cannot “pull” blood into the left ventricle; it can only allow the blood available to flow naturally into the ventricle. The human heart is also afterload sensitive in that it is responsive to the compliance and resistance in the downstream vasculature and doesn't exert excess force on the blood, which could damage the vasculature. Lastly, the left ventricle cannot deliver blood that isn't in the ventricle when it contracts; there is a limited bolus of blood that it can deliver.

10 Similarly, the pulsatile fluid pump system **301** has similar attributes of inherent safety: it is preload and afterload sensitive, and it is limited in both the volume of blood it can deliver and the force at which it can deliver that bolus of blood. When filling, the pulsatile fluid pump system **301** allows gravity filling from the venous reservoir, exerting 15 minimal negative pressure. When emptying, the linear motor **330** is inherently limited in the force that it can generate by its design. As such, it cannot overpressure the downstream tubing or vasculature, instead delivering less than the volume of blood in the pump chamber **102**, thereby only 20 delivering as much volume as the vasculature can receive.

The integral pump assembly **200** is analogous to a left ventricle of the human heart; the inlet ball check valve assembly **110** used in various embodiments hereof is analogous to a mitral valve; and the outlet ball check valve assembly **120** used in various embodiments hereto is analogous to an aortic valve. Like the human heart, the inlet **110** and outlet **120** ball check valve assemblies are passive and require a slight reversal of flow to close. This slight reversal 30 of flow mimics the slight reversal that occurs when the aortic valve of the human heart closes.

In one embodiment, of the present invention, shown in FIG. 6, a waveform program **511a** is a computer program executed by the controller system **311** microprocessor **311c** which accepts input from a set of sensors **370**, a set of user-specifiable motor parameters **401**, and a set of user-specifiable input parameters **421**. The waveform program **511a** is configured to simulate a waveform that has been 35 experimentally determined to be appropriate for embodiments of the pulsatile fluid pump system **301** of the present invention. The waveform program **511a** simulates the experimentally determined waveform by repeatedly performing a multi-piece polynomial spline algorithm **513a** and the resulting waveform is used to drive the linear motor **330**. 40 In the event that the user changes one of the user-specifiable motor parameters **401**, the waveform program **511a** uses zero or more of the current and/or previous values from the set of sensors **370**, along with the set of user-specifiable motor parameters **401**, zero or more flow characteristics **411**, zero or more user-specifiable input parameters **421**, and the current electrical waveform **512a** to create a new electrical 45 waveform **512b**. The waveform program **511a** outputs the new electrical waveform **512b**, consisting of discrete output voltages at defined time durations, at the electrical output **311b**. The electrical output **311b** is coupled to electrical input **332a** of linear motor **330**.

In another embodiment of the present invention, shown in FIG. 7, the waveform program **511b** is a computer program executed by the controller system **311** microprocessor **311c** which accepts input from a set of sensors **370**, a set of user-specifiable motor parameters **401**, and a set of user-specifiable input parameters **421**. The waveform program **511b** reads a prototype electrical waveform **512c** stored electronically within the controller system **311**. The waveform program **511b** then uses an algorithm **513b** to adjust the archetype electrical waveform **512c**. The algorithm **513b** creates a new waveform **512b** from the archetype electrical

waveform 512c using zero or more of the current and/or previous values of the set of sensors 370, along with the set of user-specifiable motor parameters 401, zero or more flow characteristics 411, zero or more user-specifiable input parameters 421, and the current electrical waveform 512a. The waveform program 511b outputs the new electrical waveform 512b, consisting of discrete output voltages at defined time durations, at the electrical output 311b. The electrical output 311b is coupled to electrical input 332a of linear motor 330.

In FIG. 8, the graphics program 611 is a computer program executed by the controller system 311, which accepts user-specifiable motor parameters 401 and user-specifiable input parameters 421. The graphics program 611 causes a set of current values of the user-specifiable motor parameters 401, a set of flow characteristics 411, and a set of user-specifiable input parameters 421 to be shown on the graphic display 400.

The operation of the waveform programs 511, graphics program 611, and graphic display 400 is discussed in further detail in the related patent, referenced above, bearing patent number 11,300,119.

FIG. 9 is a horizontal section of a pump-valving assembly 101 in accordance with an embodiment of the present invention, wherein the pump-valving assembly 101 is in diastole mode in which the chamber 102 is being filled. Fluid flows into the inlet port 111, through the first tapered tract 112, past the inlet ball 114, as that inlet ball 114 engages against the inlet ribs 115 that create gaps between the inlet ball 114 and the second tapered tract 116 that allow fluid to flow into the second tapered tract 116 and then into the chamber 102. The pump-valving assembly 101 operates in cooperation with an edge mount 202a diaphragm 202 that seats around the circumference of the chamber 102. The motion of the diaphragm in cooperation with the inlet ball 114 and the outlet ball 124 in the outlet ball check valve assembly 120 causes the flow of fluid into the chamber 102. While the chamber 102 is filling, the outlet ball 124 in the outlet ball check valve assembly 120 settles against the outlet seat 123 to prevent fluid flow from the outlet port 121 back into the chamber 102. The fluidic flywheel 103 is illustrated. The pump-valving assembly 101 is discussed in further detail in the related application, referenced above, bearing publication number 2022/0265994.

FIG. 10 is a vertical section of an integral pump assembly 200 showing a diaphragm assembly 201 mounted to a pump-valving assembly 101 in diastole mode, in which the chamber 102 is being filled. The edge mount 202a diaphragm 202 of the diaphragm assembly 201 is flexible and mounted at the edge of the chamber 102 of the pump valving assembly 101. The diaphragm 202 has an inside surface 202b for contacting a fluid in the chamber 102 to be pumped and an outside surface 202d exposed to ambient air. The integral pump assembly 200 includes a pump housing 221 including a neck 221b in which the coupler 214 reciprocates as the diaphragm 202 reciprocates. The coupler 214 contains a receptacle 214a that is sized to receive the head and a least part of the neck of push rod 342 as shown in FIG. 1. The neck 221b is configured to maintain axial alignment of the coupler 214 and (via physical features, such as flattened sides) is also configured to maintain rotational alignment of the coupler 214. The pump-valving assembly 101 is discussed in further detail in the related application, referenced above, bearing publication number 2022/065994. As the diaphragm 202 is pulled down, in a diastole mode (in a direction away from the chamber 102), to cause filling of the chamber 102, it creates a negative pressure that draws fluid

into the chamber 102 through the inlet port 111. Similarly, as the diaphragm 202 is pushed up, in a systole mode (in a direction into the chamber 102), it creates a positive pressure that causes flow of the fluid out of the chamber 102 through the outlet port 121. The integral pump assembly 200 is discussed in further detail in the related patent, referenced above, bearing patent number 11,236,741.

The embodiments of the invention described above are intended to be merely exemplary; numerous variations and modifications will be apparent to those skilled in the art. All such variations and modifications are intended to be within the scope of the present invention as defined in any appended claims.

What is claimed is:

1. A pulsatile fluid pump system comprising:
a pump-valving assembly including a chamber and a set of ports;
a diaphragm assembly coupled to the chamber and including an edge-mounted flexible diaphragm having an inside surface for contacting a fluid in the chamber to be pumped and an outside surface exposed to ambient air, and a coupler configured to reciprocate with the diaphragm;
wherein the diaphragm assembly and the pump-valving assembly are configured as an integral pump assembly, including a pump housing having a pump housing neck configured to maintain axial and rotational alignment of the coupler via flattened sides;
a control housing for removably and slidably receiving and being removably coupled to the integral pump assembly, the control housing including:
a linear motor having a magnet and a coil, the magnet reciprocating in an axial direction in relation to the coil, the coil having an electrical input;
a push rod, coupled to the linear motor, having a neck with a first radial dimension, disposed on an upper portion of the push rod, and capped by a head having a second radial dimension larger than the first radial dimension, the push rod reciprocating axially, and configured for slidable attachment to the diaphragm assembly; and
a controller system having an electrical output coupled to the electrical input of the coil, the controller system defining an electrical waveform at the electrical output to cause a desired operation of the diaphragm,
wherein the diaphragm assembly includes a slot configured to slidably receive the head and at least portion of the neck of the push rod.
2. A pulsatile fluid pump system according to claim 1, further comprising a force sensor coupled between the linear motor and the push rod.
3. A pulsatile fluid pump system according to claim 1, further comprising a flexible seal surrounding the push rod.
4. A pulsatile fluid pump system according to claim 1, further comprising a set of cooling fins thermally coupled to the coil of the linear motor.
5. A pulsatile fluid pump system according to claim 1, wherein the controller system includes a microprocessor, and the controller system is configured to execute a waveform program defining the electrical waveform at the electrical output to cause the desired operation of the diaphragm.
6. A pulsatile fluid pump system according to claim 1, wherein the integral pump assembly has a peripheral flange, and the control housing has a channel configured to remov-

ably receive the peripheral flange when the diaphragm assembly of the integral pump assembly is removably coupled to the linear motor.

7. A pulsatile fluid pump system according to claim 6, wherein at least one of the peripheral flange and the channel has a set of compliant members to physically bias the peripheral flange in the control housing.

8. A pulsatile fluid pump system according to claim 7, wherein each compliant member includes a spring.

9. A pulsatile fluid pump system according to claim 8, wherein the set of compliant members is included in a set of ball detents.

10. A pulsatile fluid pump system according to claim 1, further comprising a set of compliant members configured to removably secure the integral pump assembly to the control housing.

11. An integral pump assembly for a pulsatile fluid pump system, the integral pump assembly comprising:

a pump-valving assembly including a chamber and a set of ports; and

a diaphragm assembly coupled to the chamber and including an edge-mount flexible diaphragm having an inside surface for contacting a fluid in the chamber to be pumped and an outside surface exposed to ambient air, and a coupler configured to reciprocate with the diaphragm;

wherein the pump-valving assembly and diaphragm assembly are disposed in an integral pump assembly housing, having a pump housing neck configured to maintain axial and rotational alignment of the coupler via flattened sides, and configured to be removably coupled to a control housing for removably and slidably receiving and being removably coupled to the integral pump assembly, the control housing including a linear motor having a magnet and a coil, the magnet reciprocating in an axial direction in relation to the coil, the control housing further including a push rod having a neck with a first radial dimension, disposed on an upper portion of the push rod, and capped by a head having a second radial dimension larger than the first radial dimension, the push rod coupled to the linear motor, and also reciprocating axially, and configured for slidable attachment to the diaphragm assembly, the coil having an electrical input, wherein the electrical input of the coil is coupled to an electrical output of a controller system defining an electrical waveform at the electrical output to cause a desired operation of the diaphragm and wherein the diaphragm assembly includes a slot configured to slidably receive the head and at least a portion of the neck of the push rod.

12. An integral pump assembly according to claim 11, further comprising a set of compliant members configured to removably secure the integral pump assembly housing to the control housing.

13. An integral pump assembly for a pulsatile fluid pump system according to claim 11, wherein the integral pump assembly housing includes a peripheral flange, and the

control housing has a channel configured to removably receive the peripheral flange when the diaphragm assembly of the integral pump assembly is removably coupled to the linear motor.

14. An integral pump assembly for a pulsatile fluid pump system according to claim 13, wherein the peripheral flange has a set of compliant members to physically bias the peripheral flange in the control housing.

15. An integral pump assembly for a pulsatile fluid pump system according to claim 14, wherein each compliant member includes a spring.

16. An integral pump assembly for a pulsatile fluid pump system according to claim 14, wherein the set of compliant members is included in a set of ball detents.

17. A control housing for removably and slidably receiving and being removably coupled to an integral pump assembly for a pulsatile fluid pump system, wherein the integral pump assembly includes (i) a pump-valving assembly including a chamber and a set of ports, (ii) a diaphragm assembly coupled to the chamber and including an edge-mount flexible diaphragm having an inside surface for contacting a fluid in the chamber to be pumped and an outside surface exposed to ambient air and a coupler configured to reciprocate with the diaphragm; and wherein the pump-valving assembly and diaphragm assembly are disposed in an integral pump assembly housing having a pump housing neck configured to maintain axial and rotational alignment of the coupler via flattened sides, the control housing comprising:

a chassis;

a linear motor, rigidly coupled to the chassis, and having a magnet and a coil, the magnet reciprocating in an axial direction in relation to the coil, the coil having an electrical input;

a push rod, coupled to the linear motor, having a neck with a first radial dimension, disposed on an upper portion of the push rod, and capped by a head having a second radial dimension larger than the first radial dimension, the push rod reciprocating axially, and configured for slidable attachment to the diaphragm assembly; and a controller system having an electrical output coupled to the electrical input of the coil, the controller system defining an electrical waveform at the electrical output to cause a desired operation of the diaphragm, wherein the diaphragm assembly includes a slot configured to slidably receive the head and at least a portion of the neck of the push rod.

18. A control housing according to claim 17, wherein the integral pump assembly has a peripheral flange, the control housing further comprising a channel configured to removably receive the peripheral flange when the diaphragm assembly of the integral pump assembly is removably coupled to the linear motor.
